UNITED STATES PATENT OFFICE.

HARRY W. SMITH, OF WORCESTER, MASSACHUSETTS.

DESIGN FOR WOVEN FABRIC.

SPECIFICATION forming part of Design No. 29,752, dated November 29, 1898.

Application filed October 7, 1898. Serial No. 692,952. Term of patent 14 years.

To all whom it may concern:

Be it known that I, HARRY W. SMITH, a citizen of the United States, residing at Worcester, in the county of Worcester and Commonwealth of Massachusetts, have invented and produced a new and original Design for Woven Fabrics, of which the following is a specification.

The accompanying drawing is a face view 10 of a portion of the fabric.

The design consists of a series of members 1, composed of a plurality of woof-threads and arranged in series of three at regular intervals. Alternating with this series of horizontal members and arranged in series of 15 three at regular intervals is another set of horizontal members 2, the middle member being composed of a larger number of woof-threads than the two outer members.

The warp members 3 3 are arranged in pairs 20 at regular intervals, between which are lighter warp members.

At the point where the series of warp member 3 3 intersect the woof members 2 2 the weave is such as to produce the effect of spots 25 placed at regular intervals, which is the distinguishing feature of the design.

What I claim is—

The design for a woven fabric, as herein shown and described.

In testimony whereof I have hereunto set my hand in presence of two subscribing witnesses.

HARRY W. SMITH.
